CARL OTTO, OF ESSEN-RUHR, GERMANY

REGENERATIVE COKE OVEN

Application filed December 10, 1927, Serial No. 239,046, and in Germany December 17, 1928.

Of the regenerative coke ovens having horizontally elongated oven chambers and regenerators arranged in the longitudinal direction of the oven chambers, two types have turned out well in practice. One of them is the so-called half-divided oven, that is an oven in which the regenerators are divided into halves so as to provide two separate generators in the direction of the oven chambers, such regenerators alternating as to the direction of the draught, the heating taking place by wall halves. The other type is the twin flue oven, that is an oven, in which the same direction of draught prevails in the regenerators all over the length of the heating wall, each regenerator being in communication with the odd-numbered or with the even-numbered flues of a heating wall.

The half-divided oven affords the advantage that the regenerators, through which the combustion agents flow in different directions, abut on one another only at their narrow front ends, and that it is possible without difficulty to keep this separating wall gas-tight. This advantage is of a particular importance in ovens with regenerative pre-heating of the gas, as transitions of gas into the regenerators, that conduct waste heat, are avoided with certainty. On the other hand, the heating by wall halves is disadvantageous in that a horizontal flue must be provided for, which extends over the entire length of the heating wall. In this respect the twin flue oven is of course superior to the half-divided oven, because due to the heating by means of twin flues the horizontal flue is avoided. The twin flue ovens of the above-mentioned design suffer however from the drawback that the regenerators, alternating as to the direction of the draught, are located beside one another and thus have large separating surfaces extending over the entire length of the heating wall. It is to be understood therefor without any further explanation, that due to the presence of these large separating surfaces leakages between the juxtaposed regenerators may be avoided only with much more difficulty than in the half-divided oven.

Now my invention has for its object to fully utilize the advantage afforded both by

the half-divided oven and the twin flue oven and to avoid, on the other hand, their drawbacks. To this end, the invention substantially consists in the fact, that the regenerators extending in the longitudinal direction of the oven chambers are divided, by a gas-tight partition, into separate regenerator chambers alternating as to the direction of draught, and that each regenerator chamber is in communication, by means of a plurality of vertical ducts with a distributing channel arranged between the heating flues and the regenerators which distributing channel connects its connected regenerator, either with alternate flues or with the intermediate flues of a heating wall, a heating by twin flues being thus attained. Of course, the juxtaposed regenerators through which always flow the same agents in the same direction, and the distributing channels connected thereto may be combined so as to form one regenerator or channel.

Two embodiments of the subject-matter of my invention are illustrated by way of example in the drawings which accompany and form part of this specification. In these drawings Figures 1 and 2 relate to the first, and Figures 3 and 4 to the second embodiment, in particular.

Fig. 1 shows a vertical longitudinal section through the heating wall of a combined regenerative coke oven,

Fig. 2 is a vertical cross section the right hand half of the figure being on the lines 2-2 and the left hand half of the figure on lines 3-3 of Figure 1,

Figs. 3 and 4 show sections of the second embodiment corresponding to those of Figures 1 and 2, of the first embodiment, the right hand half of the Figure 4 being on lines 4-4, and the left hand half of the Figure 4 on lines 5-5 of Figure 3.

Fig. 5 is a horizontal detail, in section, showing strong gas distributing channels below adjacent oven chambers connected to the flues of the same heating walls.

The embodiment illustrated in Figures 1 and 2 will be described first.

Referring to these figures, *a* denotes the horizontally elongated oven chambers which

alternate in the usual manner with the heating walls the latter being subdivided so as to form twin flues b , b^1 . The regenerators extending below and in the longitudinal direction of the chambers are separated into two separate regenerators which alternate as to the direction of draught, by a partition c , in which an insulating channel c^1 is inserted which extends over the entire length of the oven battery. An air regenerator d or d^1 respectively, always alternates with a weak gas regenerator e or e^1 , respectively (e^1 not shown), reckoned in the longitudinal direction of the battery, the latter serving also to pre-heat the air, when strong gas, i.e. coke oven gas, is used. To supply the agents to be pre-heated and to lead off the waste heat the bottom channels f are provided, which may be connected in the usual way with the weak gas main g , and with the outer air or the chimney flue h , respectively. A distributing channel i extending over the entire length of the heating wall is connected to each air regenerator d , by means of a plurality of ducts d^2 which channel i is arranged between the heating flues and the regenerators and communicates with alternate flues of a pair of heating walls by means of ducts i^2 . A distributing channel k arranged beside channel i and similarly communicating with the weak gas regenerator e through ducts e^2 is likewise connected with the same alternate flues of a pair of heating walls by means of ducts k^2 . In the same manner the intermediate flues of the said pair of heating walls each communicates with a distributing channel m and a distributing channel n thru ducts m^2 and n^2 , respectively. The channels m and n are communicably connected by ducts d^3 and e^3 to the regenerators d^1 and e^1 , respectively (e^1 not shown). Distributing channels o and p arranged immediately below each chamber bottom and branched-off from the strong gas main q , serve to supply strong gas to the flues through the ducts o^2 and p^2 . The arrangement may be so chosen, that each two channels o or each two channels p are located side by side and may be so connected to the strong gas main q or cut off therefrom by means of valve q^1 , that, according to the direction of heating, only the channels o located below alternate oven chambers or only the channels p located below the intermediate chambers receive gas. In accordance with the twin flue heating each channel o and p is connected either only to alternate flues or only to the flues intermediate the alternate flues of each heating wall. Instead of the described strong gas supply the under-fire arrangement may of course be employed. The juxtaposed channels o or p may be combined so as to form one channel o and one channel p .

65 The operation of the described oven will

be clear from the above description. Besides the above-mentioned advantage afforded by my invention, the further advantage is obtained that, when the described strong gas supply is adopted, the gas-conducting channels are always separated from the idle channels by the full chamber width, so that gas transitions are avoided with certainty even with strong gas heating. An oven which is extremely reliable in service is thus offered by my invention, the construction of which oven is nevertheless not in any way more complicated than that of the combined regenerative ovens hitherto known.

For the sake of clearness of the drawings, special regulating means for the uniform distribution of gas and air are not represented. These means may be provided in a known manner, viz. for the regulation of the strong gas, replaceable gas burners in the form of nozzles may be used, and for the regulation of weak gas and air, damper bricks arranged on the bottom end of the individual heating flues are provided. The degree of admission to the regenerators may likewise be regulated by damper bricks interposed in the apertures connecting the bottom channel and regenerator chamber or in the apertures connecting the regenerator chamber with the distributing channel. Moreover the known damper bricks may be arranged on the top end of the heating flues to regulate the heating gases flowing through the individual heating flues.

The second embodiment illustrated in Figures 3 and 4 differs from that described substantially by a modified arrangement of the distributing channels disposed between the heating flues and the regenerators. For, in order to exclude with security any transitions from the weak gas channels to the waste heat channels upon leakages occurring in the distributing channels, the arrangement may be so chosen, that the gas channels are located only between air channels. When, in correspondence with the distributing channels of the first example, the air channels are denoted by i^1 , the weak gas channels by k^1 , and the waste heat channels by m^1 and n^1 , the following order results, to fulfil this condition: $i^1-k^1-i^1-m^1-n^1-m^1-i^1-k^1-i^1$ and so on.

As directly to be seen from Figure 4, each two channels i^1 and m^1 , respectively, leading to the neighboring heating walls by means of ducts i^2 and m^2 , respectively, are connected by means of ducts d^4 , d^5 to a regenerator chamber that is set each to air or waste heat, whilst each regenerator chamber adjusted to weak gas or waste heat, is only connected to a channel k^1 or n^1 , by means of ducts e^4 , e^5 which in its turn communicates the ducts k^2 , n^2 with alternate flues of a pair of heating walls. In order to obtain a supply, of the combustion agents, separately for each heat-

ing wall, the air regenerators *d* and *d*¹, respectively, may be subdivided in longitudinal direction by a transverse partition, and the weak gas regenerators *e* and *e*¹ (not shown), may also be respectively, so subdivided. The channels *k*¹ and *n*¹, respectively, are correspondingly subdivided. As to the remaining elements of Figures 3 and 4, the arrangement and mode of operation are the same as that of the first embodiment shown in Figures 1 and 2.

What I claim and desire to secure by Letters Patent is:—

1. A coke oven battery comprising a series of alternate horizontally elongated coking chambers and heating walls therefor arranged side by side in a row, each of said heating walls comprising a row of vertical combustion flues, two parallel rows of cross-regenerators arranged below said chambers, each of said rows of regenerators being adapted to operate alternately for inflow and outflow, some regenerators of each row being adapted to preheat fuel gas and the other regenerators of each row being adapted to preheat air, when operating for inflow, horizontal distributing channels above and parallel with the regenerators, ducts communicably connecting each regenerator with one of said channels, and ducts communicably connecting one of said channels with some of the flues in one of the heating walls and another of said channels with the remaining flues in the same heating wall, each channel communicably connected with a regenerator adapted to preheat fuel gas being arranged between a pair of channels, the latter being each communicably connected with a regenerator adapted to preheat air, the distributing channels communicably connected to one of the rows of regenerators being communicably connected to alternate flues in the heating walls and the distributing channels communicably connected to the other row of regenerators being communicably connected to the intermediate flues in the heating walls.

2. A coke oven battery comprising a series of alternate horizontally elongated coking chambers and heating walls therefor arranged side by side in a row, each of said heating walls comprising a row of vertical flues, two parallel rows of cross-regenerators below said chambers, each row of regenerators being adapted to operate alternately for inflow and outflow, some regenerators of each row being adapted to preheat fuel gas and the other regenerators of each row being adapted to preheat air, when operating for inflow, horizontal distributing channels located above and parallel with the regenerators, ducts communicably connecting each regenerator with one of said channels, and ducts communicably connecting each of said channels with flues of a heating wall, and means for supplying an alternative fuel gas,

comprising a pair of horizontal supply conduits below and parallel to each of the coking chambers and located between the soles of the coking chambers and the distributing channels, and ducts communicably connecting said conduits with the flues, the distributing channels communicably connected to one of the rows of regenerators being communicably connected to alternate flues in the heating walls and the distributing channels communicably connected to the other row of regenerators being communicably connected to the intermediate flues in the heating walls.

3. A coke oven battery comprising a series of alternate horizontally elongated oven chambers and heating walls therefore arranged side by side in a row, each of said heating walls comprising a row of vertical flues, regenerators extending below and in the direction of the chambers and communicably connected with the flues, a gas distributing conduit located below the bottom of each of the oven chambers, above and parallel with the regenerators, ducts communicably connecting one of the gas distributing conduits below one of the oven chambers with alternate flues in one of the heating walls and ducts communicably connecting one of the gas distributing conduits below one of the adjacent oven chambers with the intermediate flues of the same heating wall.

4. A coke oven battery comprising a series of alternate horizontally elongated coking chambers and heating walls therefor arranged side by side in a row, each of said heating walls comprising vertical flues, two parallel rows of cross-regenerators arranged below said chambers, horizontal distributing channels above and parallel to the regenerators and below the coking chambers, each of the regenerators communicating at the top thereof with one of said channels by ducts spaced from each other at the top of the regenerator, a conduit below and communicating with each of the regenerators at the bottom thereof, ducts communicably connecting the channels with said flues, each row of regenerators being adapted to operate alternately for inflow and outflow, said regenerators being jointly operable for preheating air or separately and simultaneously operable for preheating air and an extraneously derived fuel gas, and means for supplying an alternative fuel gas to the flues, comprising a pair of fuel gas conduits below and parallel to each of the coking chambers, ducts individual to the flues and communicating said fuel gas conduits therewith, said conduits being located between the soles of the coking chambers and said distributing channels.

5. In a coke oven battery, a series of alternate horizontally elongated coking chambers and heating walls therefor arranged side by side in a row, each of said heating walls comprising vertical combustion flues, cross-re-

generators located below said chambers and communicably connected with said flues, said regenerators, being jointly operable for pre-heating air, or separately and simultaneously operable for preheating air and an extraneously derived fuel gas and means for supplying an alternative fuel gas to the flues comprising a pair of conduits below and parallel to each of the coking chambers, ducts, individual to the flues, communicating said conduits therewith, said conduits being located between the soles of the coking chambers and the connections between the regenerators and the flues.

15 In testimony whereof, I have signed my name to this specification.
